CLAIM

The ornamental design for an animal trapping cage, as shown and described.

DESCRIPTION

FIG. 1 is a perspective view of an animal trapping cage showing my new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof;

FIG. 8 is bottom plan view thereof; and,

FIG. 9 is another perspective view showing the animal trapping cage in a use configuration with the doors in an open use state.

The broken lines in the drawings depict portions of the animal trapping cage that form no part of the claimed design.
